WRENCH

Horace P. Reasoner, Cheyenne, Wyo.

Application June 7, 1943, Serial No. 489,966

4 Claims. (Cl. 81—91)

My invention relates to wrenches, and has among its objects and advantages the provision of an improved pipe wrench embodying a novel adjustment to facilitate application and manipulation of the wrench under difficult operating conditions, and in which the wrench is of durable but relatively simple construction.

In the accompanying drawing:

Figure 1 is a side view of the wrench.

Figure 2 is a top view of the head structure.

Figure 3 is a bottom view, and

Figure 4 is a sectional view of the head structure.

In the embodiment of the invention selected for illustration, the wrench includes a shank 10 provided with a jaw 12 at one end thereof, which jaw is arranged at right angles to the shank and provided with gripping teeth 14. An adjustable jaw 16 is formed as a continuation of a block 18 having an opening 20 for slidably receiving the shank 10. This jaw is also provided with gripping teeth 22.

A longitudinal slot 24 is provided in the shank 10 for the reception of a slideable pivot or pin 26 attached to the block 18. Figure 4 illustrates a spring 28 as lying within the opening 20 and engaging the bottom straight edge 30 of the shank 10 to normally hold the jaw 16 in the position illustrated. This spring has an end 32 attached to the block 18, and the other end of the spring 28 slidably engages the rear face 34 of the jaw 16 so that the jaw may be pivoted about the axis of the pin 26 with the spring 28 maintaining contact with the face 30.

The upper edge of the shank 10 is provided with rack teeth 36 for selective engagement by a latch tooth 38 on the block 18 and projecting into the opening 20. The tooth 38 latches the block 18 against rearward movement on the shank 10 when the pipe is gripped between the jaws 12 and 16.

The block 18 carries two spaced arms 40 between which are located the shank 10 and a handle 42. Both the shank and the handle fit loosely between the arms 40 but are restrained from lateral movement. One end of the handle is provided with an angular end portion 44 having a pivot head 46 lying in a retaining recess 48 in the jaw 16, with the recess communicating with an opening 50 somewhat larger than the end portion 44 so that the latter may pivot relatively to the jaw 16. The handle 42 is pivotally connected at 52 with the arms 40.

In operation the jaws 12 and 16 may be adjusted to approximate positions by tapping or pressing either jaw against the work or the pipe. Such tapping will shift the block 18 longitudinally on the shank 10, with the block 18 pivoted about the axis of the pin 26 as the tooth 38 passes over the rack teeth 36. The tension of the spring 28 is sufficient to hold the tooth 38 in engagement with one of the rack teeth 36, and working grip of the jaws 12 and 16 is attained by applying pressure on the handle 42. Such pressure on the handle pivots the jaw 16 sufficiently far to cause the two jaws to attain a good bite on the work or the pipe.

Without further elaboration, the foregoing will so fully explain my invention, that others may, by applying current knowledge, readily adapt it to the same for use under various conditions of service.

I claim:

1. A pipe wrench comprising a shank having teeth and a jaw attached to one end thereof, said shank being provided with a longitudinal slot, a block having an opening slidably receiving said shank and having a second jaw, said block having a tooth selectively engageable with said teeth to hold the second jaw in different gripping positions with respect to said first jaw, said block having a pivot slideable in said slot, a spring interposed between said block and said shank opposite the teeth thereof, and a handle having a pivotal connection with said block and pivotally engaging said second jaw.

2. The invention described in claim 1 wherein said block is provided with arms straddling said shank and pivotally connected with said handle intermediate its ends.

3. The invention described in claim 1 wherein said second jaw is provided with a recess, and in which said end of the handle is pivotally retained in said recess.

4. In a wrench, a jaw having a socket therein, an arm extending from said jaw in a direction opposite its gripping face, a handle, a head formed at the inner end of the handle having swivel engagement with said socket, an element pivotally connecting the outer end of the arm with the intermediate portion of said handle, and a second jaw adjustably associated with the first mentioned jaw.

HORACE P. REASONER.
